UNITED STATES PATENT OFFICE.

WILLIAM WEST, OF DENVER, COLORADO, ASSIGNOR OF ONE-HALF TO
HOMER PENNOCK, OF NEW YORK, N. Y.

METHOD OF AND APPARATUS FOR MAKING SOAP.

SPECIFICATION forming part of Letters Patent No. 268,443, dated December 5, 1882.

Application filed April 7, 1882. (No model.)

To all whom it may concern:

Be it known that I, WILLIAM WEST, of Denver, in the county of Arapahoe and State of Colorado, have invented a new and useful improvement in method of and apparatus for making soap, and also for separating the component parts of fats and oils and obtaining from them glycerine, stearine, and oleine; and I do hereby declare that the following is a full, clear, and exact description thereof, which will enable others skilled in the art to make and use the same, reference being had to the accompanying drawings, forming a part of this specification.

15 My invention relates to a new and improved apparatus for and method of making soap, so as to very much shorten the time of the operation and produce a more perfect combination of the alkali and fatty bodies, and a perfectly-
20 neutral soap, and at the same operation save the glycerine usually wasted in making soap. It also relates to an improved method of decomposing fatty bodies into the components of glycerine, stearine, and oleine, as hereinafter described.

25 Figure 1 is a side elevation in section of the superheating-furnace, the condenser, the retort or still, and the pipe-connections and outlets. Fig. 2 is a view of the hollow inverted truncated cone in the retort or still. Fig. 3 is a view of the double cone or circulator in the retort or still.

30 A, Fig. 1, is a superheating-furnace constructed of fire-brick or other suitable material. In the lower part of the furnace is a fire-box, with grate-bars and ash-pit, and doors for supplying fuel and cleaning out the furnace, as shown at *a b c d*.

35 B is an arrangement of flasks and pipes for superheating the steam, preferably made of a series of wrought-iron flasks connected together by wrought-iron pipes, as shown. The size of the flasks and pipes is varied according to the capacity of the apparatus. One 40 end of the pipe connected to the flasks passes up through the top of the furnace, as shown at *B'*. The other end passes out at the side of the furnace and enters the top of the retort or still, as shown at *B²*.

45 C is a retort or still, made of any suitable metal or material capable of resisting a press-

ure of two hundred and fifty pounds to the inch. The body of the retort or still is made round or boiler-shaped, the height being greater than the diameter, as shown in the drawings.

55 Inside of the retort or still, is a hollow inverted truncated cone or funnel-shaped piece, *C'*. (Shown in Fig. 2.) This piece is made of copper or iron. The upper or large end is attached to the inside of the retort or still by strips of metal, as shown at *C²*. The lower end passes down to or near the center of the retort or still, as shown.

60 Directly below the cone *C'* is a double hollow cone or funnel-shaped piece, *C³*. (Shown in Fig. 3.) This piece is curved at the large ends and is joined together at the small part, as shown at *C⁴*. I call this piece a "circulator." It is made of copper or iron. The upper part 65 is attached to the retort or still by strips of metal in the same manner as *C'*. The hollow inverted truncated cone or funnel-shaped piece *C'* enters into the small part of the double cone *C³*, as shown. The steam-pipe from the super-heater (shown at *B²*) passes down into and 70 near the lower part of the cone *C'*.

75 The retort or still *C* is provided with a top opening, *e*, which is secured steam-tight by a door or man-hole cover. It also has pipe-openings *ff* near the top, through which the liquefied fat or oil and alkali can be charged into it. The retort or still can be charged through the top opening, *e*.

80 *g* is an outlet near the bottom, for the purpose of discharging the contents or cleaning it out.

85 *D* is a condenser, made of any suitable water-tight material and of any shape required. It is divided through the center by a partition, *g*. *E*. Near the top in the partition is an overflow-opening, *E'*. It is also provided with a cold-water pipe, *I*, near the bottom, and an overflow opening or pipe, *J*, near the top.

90 *F* and *F'* are two receivers in the condenser. They are made of metal or any suitable material of any shape or size required. They have cocks or valves at the bottom for drawing off the contents, as shown at *h*.

95 *I²* is a safety-valve attached to the pipe *G* near the retort or still.

100 *G* is a pipe leading from the retort or still *C*.

to the receiver F. This pipe passes down into the receiver nearly to the center, as shown.

G' is a pipe connecting the two receivers. This pipe connects with the top of the receiver F and passes through the partition E and down into the receiver F', as shown.

H is a pipe from the top of the receiver F', through which the uncondensed matter and steam are conveyed away.

10 I is a cold-water pipe for supplying the condenser D. Water is allowed to flow through this pipe into the part of the condenser surrounding the receiver F'. When the water rises up to the opening E' it will overflow and fill the opposite side of the condenser. When both sides are full the water will overflow through the opening or pipe J at the top of the condenser. By this arrangement of condenser and water-supply the receivers are maintained at different degrees of temperature, so that a part of the products are condensed in each. The difference in temperature is secured by the water entering cold at I and passing into the second division through the opening E' in the partition E. Thus the water in the second division can be maintained at 180° all the time.

K is a frame or platform on which the condenser rests.

The operation of my apparatus is as follows: 30 The fuel in the superheating-furnace having been ignited, and the fatty matter and alkali or other substances to be acted upon is placed or run into the retort or still C, the condenser-tank is filled with water, and a steam-pipe from a steam-boiler or any source of live steam is connected to the superheater-pipe B'. Steam is allowed to flow into the superheater and is heated to 440° Fahrenheit. The steam thus heated enters the retort or still C through the 40 pipe B², which passes down to near the point or bottom of the cone C' and strikes the fatty bodies with immense velocity and causes them to circulate in the direction of the arrows, and the action is continued until decomposition is 45 complete and the materials are carried over into the receivers F and F' through the pipes G and G'.

The advantages of my invention are as follows:

50 First. A great saving in labor and expense. In the methods heretofore practiced in soap-boiling the fats float on the top of the lye, requiring many hours to combine. By my method and apparatus the circulation brings both in

violent contact at once and continuously, and a better soap is made in half an hour than can be made in twenty-four hours by the boiling process.

Second. Saving the glycerine contained in the fat and oil used in making soap, which by the old process is lost, amounting to millions of pounds a year. By my process the glycerine is distilled over and condensed in the receiver F, from which it can be drawn off and saved.

Third. My invention is equally applicable to the rapid decomposition of fats and oils into stearic and oleic acids and glycerine.

Fourth. The construction and arrangement of the condenser D, whereby the different degrees of temperature can be maintained.

I am aware that superheated steam has been used in a plain retort or still for refining purposes and is not new; but I am not aware that superheated steam has been applied to a retort or still constructed substantially the same as my invention and producing the effect claimed by me.

Having fully described my invention, what I desire to claim, and secure by Letters Patent, is—

1. The retort or still C, constructed of any suitable material, and with a hollow inverted truncated cone, C', and a double hollow cone or circulator, C³, inside the retort or still and attached to it, substantially as shown and described.

2. In a soap-making apparatus, the employment of a jet of superheated steam introduced into a hollow inverted truncated cone and circulator in the center of a retort or still, substantially as and for the purpose set forth.

3. The condenser D, constructed with the receivers F and F', inside the water-tank, and arranged to receive its supply of cold water near the bottom of the second or last tank, so as to condense the glycerine and other products of the retort or still at different degrees of temperature, substantially as described.

4. In a soap-making apparatus, the combination of the following elements: the superheating-furnace A and superheater B, the retort or still C, with its center cones, and the condenser D, substantially as shown and described.

WILLIAM WEST.
